UNITED STATES PATENT OFFICE

156,669

COUNTER SERVICE UNIT OR SIMILAR
ARTICLE

Roy V. Runnels, Hattiesburg, Miss.

Application October 7, 1947, Serial No. 141,794

Term of patent 14 years

(CL. D44—22)

To all whom it may concern:

Be it known that I, Roy V. Runnels, a citizen of the United States, residing at Hattiesburg, in the county of Forrest and State of Mississippi, have invented a new, original, and ornamental Design for a Counter Service Unit or Similar Article, of which the following is a specification, reference being had to the accompanying drawing, forming part thereof.

Figure 1 is a perspective view of a counter service unit, or similar article, showing my new design.

Figure 2 is a side elevational view of the same, Figure 3 is a rear elevational view, and Figure 4 is a plan view.

I claim:

The ornamental design for a counter service unit or similar article, substantially as shown.

ROY V. RUNNELS.
